UNITED STATES PATENT OFFICE.

STEPHEN D. BAKER, OF NEW YORK, N. Y.

DESIGN FOR A SOAP-DISH.

48,482.

Specification for Design.

Patented Feb. 1, 1916.

Application filed October 28, 1915. Serial No. 58,503. Term of patent 7 years.

To all whom it may concern:

Be it known that I, STEPHEN D. BAKER, a citizen of the United States, residing in the city of New York, county of New York, State of New York, have invented a new, original, and ornamental Design for a Soap-Dish, of which the following is a specification, reference being had to the accompanying drawing, forming a part thereof.

The drawing shows the soap dish in Figure 1, in top plan; Fig. 2, in end elevation;

Fig. 3, in side elevation; Fig. 4, in underneath plan; Fig. 5, in section on the line $x-x$ in Fig. 1; and, Fig. 6, on the line $y-y$ in Fig. 1.

I claim:

The ornamental design for a soap dish, substantially as herein shown.

STEPHEN D. BAKER.
